(57) **CLAIM**

The ornamental design for a fork lift truck, as shown and described.

DESCRIPTION

FIG. 1 is a perspective front view of a fork lift truck showing our new design;

FIG. 2 is a perspective rear view thereof;

FIG. 3 is a right side elevation view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom view thereof.
